UNITED STATES PATENT OFFICE.

WILLIAM A. LORENZ, OF WEST HARTFORD, CONNECTICUT, ASSIGNOR TO THE OTAKA FABRIC COMPANY, OF WEST HARTFORD, CONNECTICUT, A CORPORATION OF CONNECTICUT.

BARREL-LINING MACHINE.

Application filed January 11, 1927. Serial No. 160,399.

This invention relates to a machine for the production of barrel linings such as are shown in my co-pending application Serial No. 38,701, filed June 22, 1925. My improved barrel lining has a body portion which is longitudinally corrugated so that the lining can readily accommodate itself to the shape of the barrel, and this body portion is non-stretchable longitudinally so that it is more or less stiff in the direction of its length and will hold its shape and position within the barrel until the lining is filled with the contents. One end at least of the barrel lining is rendered flexible in all directions by double creping it so that the end which is thus double creped may be readily folded over. If desired, the lower end of the lining may also be rendered flexible in all directions as well as the upper end which is to constitute the mouth.

The aim of the present invention is to provide an improved, practical machine for economically producing barrel linings of this kind.

In the accompanying drawing, wherein I have shown, for illustrative purposes, one of the many embodiments which the improvements of the present invention may take:

Figure 1 is a plan view of my improved machine;

Fig. 2 is a side view thereof; and

Fig. 3 is a view showing a barrel lining such as is disclosed in my said application Serial No. 38,701.

Referring to the drawings in detail, the frame of the machine may be of any suitable construction, but it is here illustrated as having two side frames 10, 10 tied together by braces or rods 11. The roll of paper 12 is supported on a shaft 13 journaled in suitable brackets 14 located at one end of the frame. A drag is exerted on the paper roll by means of a strap 15 secured to a rod 16 and carrying a weight 17.

The paper web 18 is drawn forwardly over a roll 19 from which it passes downwardly into a tank 20 and under the rolls 21. The water in this tank may be heated by steam coils 22. The wet paper then passes upwardly, as at 23, and onto a cylinder 24 upon which the corrugating and creping operations are performed, as hereinafter described more in detail. The cylinder 24 is fixed to a shaft 25 supported in suitable

brackets 26. The shaft 25, together with the cylinder thereon, is driven in a clockwise direction from a main shaft 28 through a pinion 29 and a gear 30. This drive shaft is suitably journaled in the frame and may have a drive pulley 31. The gear 30 meshes with a gear 33 fixed to a shaft 34 journaled in slidably bearing boxes 35 behind which are springs 36, the pressure of which may be adjusted by screws 37. On this shaft is a rubber faced roll 38 which is pressed against the paper by the springs 36 as the paper passes between this roll and the cylinder. This roll 38 is preferably co-extensive with the crinkling cylinder 24 and serves to squeeze excess water out of the paper and cause the paper to adhere to the crinkling cylinder. Above the roll 38 and fixed to the shaft 39, journaled in slidable bearing boxes 40, is a roll 41 which is pressed against the crinkling cylinder by springs 42 located behind the bearing boxes 40. These springs may be adjusted by the screws 43. 44 is a doctor blade which will be described herein-after more in detail. After the paper web has been corrugated and crinkled, as herein-after described, the web is carried away from the machine by a belt 45.

In accordance with the present invention, the crinkling cylinder 24, the roll 41 and the doctor blade are so constructed and arranged that the body portion of the web is transversely corrugated, as at 50, and at least one marginal or edge portion of the web is corrugated in the direction of the length of the web and is cross crinkled so that the edge or margin, or edges or margins, as the case may be, are flexible and stretchable in all directions. In the present instance, wherein is illustrated a machine whereby the barrel linings produced are flexible in all directions at both ends, as at 51, the cylinder 24 has at each end annular or circumferential corrugations, and between these circumferentially corrugated portions, the cylinder is longitudinally corrugated. The circumferentially corrugated portions of the cylinder are designated by the character 24^a, and the central longitudinally corrugated portion by the character 24^b. Furthermore, in the present disclosure, the circumferential ribs of the portions 24^a are grooved or corrugated in the direction of the length of the cylinder and in registry with the corrugations of the portion 24^b so that, in effect,

there is provided, on each end of the roll, circumferential rows of projections. The cylinder 24 is preferably made of chilled iron but may be constructed of any other suitable material. The roll 41 is corrugated lengthwise in accordance with the longitudinally extending corrugations of the cylinder so that the roll 41 and the cylinder mesh, so to speak, with the result that the 10 wet web, as it passes between this roll and the cylinder, is transversely corrugated, that is to say, the corrugations on the roll 41 cause the paper to assume the longitudinally corrugated shape of the cylinder. The doctor 15 blade is provided, at each end, with a serrated portion 44^a which is adapted to cooperate with the circumferentially corrugated portion 24^a of the crinkling cylinder. By serrating the ends of the doctor blade, 20 teeth are provided which project into the grooves between the circumferential corrugations or ribs on the crinkling cylinder. The portion 44^b of the doctor blade, and which portion is located between the serrated portions 44^a, is out of engagement with the crinkling cylinder and the paper carried 25 thereby.

The operation of the machine is briefly as follows: The paper is drawn through the 30 tank 20 and onto the crinkling cylinder against which it is firmly pressed by the rubber faced roll 38. This roll causes the web to adhere to the cylinder and presses excess water from the web. The cylinder carries the paper web between itself and the corrugated roll 41 with the result that the 35 paper is forced into the longitudinally extending grooves in the crinkling cylinder whereby the web is transversely corrugated. 40 The cylinder then carries the paper up against the doctor blade, with the result that the edge or marginal portions of the web are crinkled transversely of the longitudinally extending corrugations which 45 have been formed in these marginal edges. The marginal portions of the web are thus double crinkled, so to speak, that is to say, they are rendered elastic and flexible in all directions, and the body or central portion of 50 the web is longitudinally corrugated but is not crinkled.

In Fig. 3, I have shown, by way of illustration, one form of barrel lining which may be made by the use of the present machine. 55 In this instance, the lining is shown as having both ends double crinkled, but it is within the spirit of the invention to double crinkle but one end and, preferably, that end which is to cover the mouth of the bar-

rel in which the lining is to be positioned. 60 A barrel lining of this sort is relatively stiff in its body portion so that it will retain its shape when placed in a barrel until it is filled and, since the end portions are flexible in all directions, they may be readily folded 65 over. The body portion of the lining may expand radially or laterally so as to take the form of the barrel when the lining is filled.

I claim as my invention:

1. In a paper creping apparatus of the 70 character described and in combination, a supporting surface provided with a longitudinally corrugated portion and a transversely corrugated portion, means for causing paper to take the shape of said surface, 75 and a blade cooperating with the transversely corrugated portion whereby the paper passing thereover is crinkled.

2. In a paper creping apparatus of the 80 character described and in combination, a cylinder having a portion of its periphery longitudinally corrugated and a second portion circumferentially corrugated, and a doctor blade cooperating with the circumferential corrugations for crinkling the paper 85 carried upon such portion.

3. In a paper creping apparatus of the character described and in combination, a cylinder having a portion longitudinally corrugated and a portion at one end provided 90 with circumferentially corrugations, a roller cooperating with said cylinder for forcing the paper into said corrugations, and a doctor blade cooperating with the circumferentially corrugated portion of said cylinder 95 for crinkling the paper carried thereby.

4. In a paper creping apparatus of the character described and in combination, a cylinder having a longitudinally corrugated portion and a portion at one end provided 100 with circumferential corrugations, means for wetting the paper delivered to said cylinder, means for pressing the paper against said cylinder, and a doctor blade cooperating with said circumferential corrugations 105 for crinkling the paper carried thereby.

5. In a paper creping apparatus of the character described and in combination, a cylinder longitudinally corrugated, said cylinder having at one end circumferential 110 corrugations extending across the longitudinal corrugations, means for pressing the paper delivered to said cylinder against the same, and a doctor blade cooperating with the circumferential corrugations for crinkling the paper carried thereby. 115

WILLIAM A. LORENZ.
